UNITED STATES PATENT OFFICE.

WILLIAM B. MASON, OF BOSTON, MASSACHUSETTS, ASSIGNOR TO THE MASON REGULATOR COMPANY, OF SACO, MAINE, A CORPORATION OF MAINE.

FUEL-SUPPLYING APPARATUS FOR LIQUID-HYDROCARBON BURNERS.

No. 839,780.

Specification of Letters Patent.

Patented Dec. 25, 1906.

Application filed August 15, 1901. Serial No. 72,131.

To all whom it may concern:

Be it known that I, WILLIAM B. MASON, a citizen of the United States, residing at Boston, in the county of Suffolk, State of Massachusetts, have invented a certain new and useful Improvement in Fuel-Supplying Apparatus for Liquid-Hydrocarbon Burners, of which the following is a specification, reference being had therein to the accompanying drawings.

The invention consists in general in improvements in the apparatus which is employed for supplying fuel to burners consuming liquid hydrocarbon—such, for instance, as those which are used in connection with self-propelled or motor vehicles and the like.

The invention has been designed with its use in combination with the burners of self-propelled or motor vehicles more especially in mind; but it will be clear that it is not limited to this precise use and that it may be employed elsewhere as well. In the drawings for convenience I have represented the same as employed upon a self-propelled or motor vehicle, and I will thus describe the same.

The invention consists in an auxiliary system which is combined with the main or usual gasoline system, as hereinafter explained, and a by-pass by means of which the two systems are relieved in case of accident such as will be described.

In the drawings, Figure 1 is a view on the order of a diagram, illustrating the various features of the invention and the manner of reducing the invention to practice, certain parts being in elevation and others in vertical section. Fig. 2 is a view showing the force-pump and the means of operating the same. Fig. 3 is a view of the relief device in central vertical section.

Having reference to the drawings, at 2, Fig. 1, is intended to be represented a boiler of any of the kinds commonly in use on vehicles such as have been referred to, and at 3 is intended to be indicated a burner such as is employed in connection with the said boiler. Only the exteriors of the boiler and burner are represented, since the said parts may be of any usual or suitable character and construction.

4 designates a pipe through which the liq-

uid - hydrocarbon fuel, hereinafter termed "gasoléne," inasmuch as gasoline is the substance most commonly in use at the present time, finds its way to the burner 3. The usual holder or container for gasoline is intended to be indicated at 5, the said pipe 4 being in communication therewith, as shown. 6 is a pipe leading from the said container 5 and communicating with the pipe 4 at a point adjacent the burner 3, as shown. Pipe 4 is furnished with a hand-valve at 41, intermediate the container 5 and the point of connection at 61 between the pipes 6 and 4 and 65 adjacent the said point of connection; by means of which hand-valve the flow through pipe 4 from the container 5 to the burner 3 may be controlled as required. When hand-valve 41 is opened prior to starting up, the 70 gasoline is forced through pipe 4 to the burner through the expansive power of compressed air within the upper portion of the container 5. After starting up and when the power-pump, hereinafter referred to, is set in motion the hand-valve 41 is closed again. The pipe 6 has a similar hand-valve 62 adjacent the container, by means of which the flow of gasoline from the container through the said pipe 6 may be regulated. 80

7 designates a power-operated force-pump which is combined with the pipe 6 for the purpose of forcing gasoline through the same to the burner, the said pump being actuated from the engine in connection with which 85 the burner and boiler are employed in practice. In Fig. 2 said engine is shown at 72 and the piston-rod thereof at 73. A pin 74, connected with said piston-rod, works in the slot 75 of a lever 76, the said lever being pivoted at 77 and being connected with the piston-rod 78 of said force-pump. 8 is a hand-pump, also combined with the said pipe 6, by means of which, when necessary, gasoline may be forced through the pipe 6 toward the 95 burner—as, for instance, when the engine is not running.

71 71 and 81 are check-valves adjacent the power-pump 7 and hand-pump 8, respectively, for the purpose of preventing 100 backflow of gasoline through the pipe 6.

9 is a hand-operated air-compressing pump which usually in practice is mounted at the front of the vehicle, 10 being a pipe which

leads from the said pump to and connects with another pipe 11, the latter being in communication with a pipe 12, leading to the gasolene - container 5. By means of the 5 pump 9 air is forced through the pipes 10, 11, and 12 into the container 5 and compressed in said container until a sufficient pressure is secured to insure proper feed of the gasolene to the pump, when required, 10 through pipe 4.

13 is a pressure-gage employed in connection with the pipe 12, and 14 is a three-way cock at the point of union of the pipes 11 and 12, by means of which the flow of air through 15 the said pipe may be controlled as herein-after referred to. The gage 13 enables the degree of pressure within the container 5 to be ascertained.

The purposes and mode of operation of the 20 parts and connections thus far described are familiar and well understood.

In conformity with my invention I provide an auxiliary container 15, also in communication with the pipe 11, the said pipe 11 25 being extended in opposite branches from the point of connection 102 of the pipe 10 therewith, the respective branches leading to the container 5 and auxiliary container 15, respectively.

30 At 111 is a hand - operated valve with which the pipe 11 is provided between the auxiliary container 15 and the point 102 of connection of the pipe 10 with said pipe 11, and by means of which hand-valve 111 communication between the air-pump 9 and the auxiliary container 15 through the said pipe 11 may be controlled. Pipe 16 leads from the auxiliary container 15 and connects with the feed - pipe 6 at 161. In preparing for 35 operation air is pumped into the container 5 until the required pressure is produced within the same, the valve at 111 having been closed. Air then is pumped into the said auxiliary container 15, the cock at 14 having been turned so as to disestablish 40 connection between the pipe 11 and the container 5 through the pipe 12. The said cock, however, maintains connection between the pipe 11 and the indicator 13, so as to indicate 45 the pressure which is secured within the auxiliary container 15.

During the regular working of the engine and connected apparatus such portion of the 50 volume of gasolene which is forced through the pipe 6 toward the burner 3 by the stroke of the pump 7 as is in excess of the rate of discharge through the burner finds its way 55 through the pipe 16 into the auxiliary container 15 and is accumulated in the latter.

60 The purpose of the auxiliary container 15 is to receive and store up under pressure a supply of gasolene which shall be available for use in feeding the burner 3 at a time when the feed by means of the pump at 7 is arrested 65 or suspended for any reason or by any cause

whatever. Thus if during the running the main system should become deranged or exhausted of its fuel-supply the required feed of gasolene would be kept up from the auxiliary container 15. In connection with 70 the said auxiliary container 15 I provide means whereby after a predetermined pressure within the said container has been secured through the gradual forcing of the excess fuel-supply into the same relief is afforded by permitting the excess feed of gasolene to find its way back to the container 5. Thus with the pipe 16 I connect a pipe 17, leading to a needle-valve at 18, (shown in section in Fig. 3,) the latter being in communication through a pipe 19 with the pipe 4. 75

In Fig. 3 the coupling which connects pipe 17 with the needle-valve is supposed to be indicated at 172. Pipe 17 is furnished with a hand-operated valve 171, by means of 80 which communication through the said pipe with the needle-valve at 18 may be controlled, and the pipe 19 also is furnished with a hand-operated valve at 191, by means of which communication with the pipe 4 85 through the needle-valve 18 and the pipe 19 may be controlled. The needle-valve is of a self-acting variety intended normally to remain closed, so as to preclude the return of gasolene past the same to and through 90 pipe 4 to the container 5. It ordinarily remains closed during the regular action of the apparatus. When, however, the predetermined pressure within the auxiliary container 15 is attained in consequence of the 95 gradual increase in the quantity of excess fuel which has entered the same, the needle-valve 18 opens, permitting flow to take place past the same toward the container 5.

Usually in practice the needle-valve 18 100 will have the needle 183, Fig. 3, thereof connected with and operated by a diaphragm 184 of usual character, the case for the said diaphragm being indicated at 181 and the continuation of the said casing, which 105 encloses the diaphragm-spring 185, being indicated at 182. If for any reason the diaphragm should break, there would be nothing to move the needle so as to open the needle-valve when the gasolene-pressure reaches 110 the predetermined degree. In order to avoid 115 injury to the apparatus as a result of such breakage of the diaphragm, I provide a bypass which is constituted by a pipe 20, communicating with the spring-chamber of the 120 portion 182 of the casing above the diaphragm and also communicating with the pipe 19 below the seat of the needle-valve 18, with which the needle coacts.

In Fig. 3 the communication in the latter 125 connection is through a small passage 201 in the body of the lower portion of the needle-valve. When now the diaphragm breaks, the excess feed of gasolene finds its way 130 through the diaphragm-casing and the said

by-pass pipe 20 into the pipe 19 and through the latter and the pipe 4 back to the container 5.

What I claim is—

- 5 1. In combination, the burner, the liquid-fuel container, a pipe connecting said burner and container and through which the fuel flows under air-pressure, a second feed-pipe also communicating with the said container

10 and burner, the power feed-pump whereby the fuel from said container is impelled through the latter pipe to the burner, the auxiliary container connected with said second pipe and receiving a portion of the fuel

15 which is fed through the same, and means for forcing air into the respective containers to produce air-pressure in each thereof.

2. In combination, the burner, a liquid-fuel container, a pipe connecting said burner and container and through which the fuel flows under air-pressure, a second feed-pipe also communicating with the said container and burner, a power-pump by which the fuel is impelled through the latter pipe to the

25 burner, the auxiliary container connected with the said second pipe and receiving a portion of the fuel which is fed through the same, the air-pump, piping connecting the said pump with the respective containers,

30 and means whereby communication between the pump and the respective containers is controlled.

3. In combination, the burner, the liquid-fuel container, a pipe connecting said burner and container and through which the fuel flows under air-pressure, a second feed-pipe also communicating with the said container and burner, the power-pump by which the fuel is impelled through the latter pipe to the

35 burner, the auxiliary container connected with said pipe and receiving a portion of the fuel which is fed through the pipe, the air-pump, piping connecting the said pump with the respective containers, a pressure-gage,

40 and means whereby communication between the said air-pump and the respective containers is controlled and means whereby said pressure-gage is placed in communication with the container into which air is being

45 forced at a given time.

50 4. In combination the burner, the liquid-fuel container, a pipe connecting said burner and container and through which the fuel flows under air-pressure, a second feed-pipe

also communicating with the said container and burner, the power-pump by which the fuel is impelled through the latter pipe to the burner, the auxiliary container connected with said second pipe and receiving a portion of the fuel which is fed through the pipe, means for forcing air into the respective containers to produce air-pressure in each thereof, and a relief device whereby when an excess of pressure is produced by the action of the pump a portion of the fuel impelled forward by the pump is permitted to return to the container.

5. In combination, the burnér, the liquid-fuel container, a pipe connecting said burner and container and through which the fuel flows under air-pressure, a second feed-pipe also communicating with the said container and burner, the power-pump by which the fuel is impelled through the latter pipe to the burner, the auxiliary container connected with said second pipe and receiving a portion of the fuel which is fed through the pipe, means for forcing air into the respective containers to produce air-pressure in each thereof, and a connection between said pipes provided with a relief-valve whereby when an excess of pressure is produced by the pump a portion of the fuel impelled forward by the pump is permitted to return to the container. 70 75 80

6. In combination, the burner, the liquid-fuel container, a pipe connecting said burner and container and through which the fuel flows under air-pressure, a second feed-pipe also communicating with the said container and burner, the power-pump by which the fuel is impelled through the latter pipe to the burner, the auxiliary container connected with said second pipe and receiving a portion of the fuel which is fed through the pipe, means for forcing air into the respective containers to produce air-pressure in each thereof, and a connection between said pipes provided with a diaphragm-valve whereby when an excess of pressure is produced by the pump a portion of the fuel impelled forward by the pump is permitted to return to the container. 85 90 95 100

In testimony whereof I affix my signature
in presence of two witnesses

WILLIAM B. MASON.
